UNITED STATES PATENT OFFICE.

GEORGE B. SCHMIDT, OF NEW YORK, N. Y.

DESIGN FOR A LOCK AND HINGE FASTENER FOR BOXES.

SPECIFICATION forming part of Design No. 33,777, dated December 25, 1900.

Application filed November 6, 1900. Serial No. 35,678. Term of patent 7 years.

To all whom it may concern:

Be it known that I, GEORGE B. SCHMIDT, a citizen of the United States, and a resident of the city of New York, borough of Brooklyn, in the county of Kings and State of New York, have invented and produced a new and original Design for a Lock and Hinge Fastener for Boxes, of which the following is a specification, reference being had to the accompanying drawings, forming a part thereof, in which—

Figure 1 is a perspective view of a lock and hinge fastener for boxes embodying the features of my design, and Fig. 2 is a plan view 15 of the same.

The design consists in the straight body member A, the branch member B, projecting from one end of the body member at approximately right angles, and the second branch

member C, projecting from the other end of the body at approximately right angles and in a different vertical plane from that of the member B, the member C terminating in an open loop D, lying in the same plane therewith and appearing in plan view to be crossed 25 by the member B.

Having thus described my invention, I claim as new and desire to secure by Letters Patent—

The design for a lock and hinge fastener 30 for boxes as herein shown and described.

In testimony whereof I have signed my name to this specification in the presence of two subscribing witnesses.

GEORGE B. SCHMIDT.

Witnesses:

J. FRED ACKER,
JNO. M. RITTER.
